US0D1073074S

(12) **United States Design Patent** (10) **Patent No.:** **US D1,073,074 S**
(45) **Date of Patent:** **** Apr. 29, 2025**

(54) **VESSEL CLOSING DEVICE**

(71) Applicant: **CATHETER PRECISION, INC.**, Fort Mill, SC (US)

(72) Inventor: **David Jenkins**, Flanders, NJ (US)

(73) Assignee: **CATHETER PRECISION, INC.**, Fort Mills, SC (US)

(**) Term: **15 Years**

(21) Appl. No.: **29/862,677**

(22) Filed: **Dec. 12, 2022**

(51) LOC (15) Cl. **24-02**

(52) U.S. Cl.

USPC **D24/169**

(57) **CLAIM**

The ornamental design for a vessel closing device as shown and described.

DESCRIPTION

FIG. 1 is a perspective view of the vessel closing device. FIG. 2 is a left side view of the vessel closing device. FIG. 3 is a right side view of the vessel closing device. FIG. 4 is a first end view of the vessel closing device. FIG. 5 is a second end view of the vessel closing device. FIG. 6 is a top view of the vessel closing device; and, FIG. 7 is a bottom view of the vessel closing device. The broken lines illustrate portions of the vessel closing device that form no part of the claimed design.

1 Claim, 7 Drawing Sheets
